UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,098, dated September 22, 1896.

Application filed August 5, 1896. Serial No. 601,833. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of an arrangement of groups of flowers and leaves connected by festoons of flowers and leaves, as represented in the accompanying drawing.

15 The border for said design consists of festoons of flowers and leaves hanging from ornamental scrolls forming the top of the border, and an ornamental band below the festoons of flowers and leaves forming the bottom of the border, as shown in the drawing.

What I claim is—

- 20 1. The design for wall-paper herein shown and described.
2. In the design for wall-paper the border herein shown and described.

Witness my hand this 1st day of August, 25 1896.

CHARLES BOOZ.
